UNITED STATES PATENT OFFICE

171,309

TOOL HANDLE

Jacob Sackstein, Portsmouth, Va.

Application July 23, 1953, Serial No. 26,112

Term of patent 7 years

(Cl. D93—4)

To all whom it may concern:

Be it known that I, Jacob Sackstein, have invented a new, original, and ornamental Design for a Tool Handle, of which the following is a specification, reference being had to the accompanying drawing, forming a part hereof.

I claim:
The ornamental design for a tool handle, as shown.

JACOB SACKSTEIN.
